UNITED STATES PATENT OFFICE.

WELDON E. PENTICOFF, OF FERGUS FALLS, MINNESOTA.

ADVERTISING CALL SHEET.

Application filed June 14, 1924. Serial No. 719,396.

To all whom it may concern:

Be it known that I, WELDON E. PENTICOFF, a citizen of the United States, residing at Fergus Falls, in the county of Otter Tail and State of Minnesota, have invented certain new and useful Improvements in Advertising Call Sheets, of which the following is a specification.

This invention relates to improvements in hotel call sheets and has as its primary object to provide a call sheet so constructed that it will constitute a valuable advertising medium. As is well known, it is customary, in hotels, to provide, daily, a sheet upon which the clerk may write the room number which is to be called at any hour requested by the guest occupying such room, and ordinarily these sheets are loose and possess no advantage other than that contemplated by their ordinary usage and, therefore, the invention contemplates providing a number of such sheets, a backing therefor, and means providing for display of advertising matter.

Another object of the invention is to so construct the article that the advertising matter will be clearly presented to the view of the guests standing at or approaching the desk or counter of the hotel clerk, the call sheets of the article being, on the other hand, arranged so as to be readily observed by the clerk.

Another important object of the invention is to provide means for effectually protecting the advertising matter from defacement and yet provide for ready substitution of one card of advertising for another card.

In the accompanying drawings:

Figure 1 is a perspective view of the advertising call sheet embodying the invention.

Figure 2 is a vertical sectional view through the article taken on the line 2—2 of Figure 1, looking in the direction indicated by the arrows.

The article comprises a base or backing indicated by the numeral 1 and which may be of cardboard, fiber board, metal, or, in fact, any material found suitable for the purpose, the backing being preferably light in weight and yet of a relatively stiff material. The said backing or base is of rectangular form and a binding 2 of leather, leatherette, or any other suitable material, is applied about the margin of the backing and united thereto as, for example, by stitching, as indicated by the numeral 3. The binding 2 is applied about the margins of

the backing so as to cover the edge of the backing and extend over the upper and under faces of the said backing at the marginal portions thereof, and preferably, the portion of the binding which extends beneath the backing will be of sufficient width to firmly sustain the article when it is laid flat upon a counter or other flat surface. If desired, the binding may be in the form of a sheet of suitable material entirely covering the under surface of the backing and having its marginal portions turned over the margin of the backing 1.

The line of stitching 3 serves also to marginally secure, upon the upper side of the backing 1, a sheet or pane 4 of celluloid, or any other transparent material found suitable for the purpose, and this sheet or pane, being secured at its lateral and one transverse edges, constitutes, in connection with the backing 1, a pocket in which is removably inserted a card 5 bearing one or more advertisements as indicated by the numeral 6. It will be observed by reference to the drawings that the sheet or pane 4 is located at one end of the backing 1 and that the mouth of the pocket formed by this sheet is presented toward the opposite end of the said backing.

The numeral 7 indicates a pad of call sheets each of which is printed or ruled to provide vertical blank columns indicated by the numeral 8. At the upper ends of the columns are printed hours and fractions of hours, as indicated by the numeral 9 and beginning, for example, at 6 A. M. and extending to noon, and between the upper and lower ends of the columns there are printed other hours and fractions thereof indicated by the numeral 10, which may run, for example, from 1 A. M. to 5:45 A. M. The call sheets do not differ materially from the ordinary call sheets employed in hotels, and by reference to Figure 1, it will be observed that the sheets are disposed, in a bank, upon the upper face of the backing 1, so that the top of the sheets will be located at the mid-portion of the backing 1, the advertising card 5 being likewise positioned, so that the said advertising card may be readily consulted by one standing in front of the clerk's counter or desk, and, on the other hand, the clerk may readily consult the call sheets.

In securing the bank of call sheets to the backing 1, the said backing is formed with openings 11 and the sheet or pane 4 is like-

wise formed with openings 12, the said openings 11 and 12 being in registration. Bolts 13 are fitted through these openings with their heads 14 flush with the under face of 5 the backing 1, and thumb nuts 15 are fitted onto the bolts and may be tightened to bear against the uppermost call sheet of the bank or pile. In view of the fact that the bolts 13 pass through the backing 1, the free margin 10 of the sheet or pane 4 and the upper marginal portion of the bank of call sheets 7, and the said upper marginal portions of the said sheets 7 overlap the free marginal portion of the sheet or pane 4, the mouth of the 15 pocket in which the advertising card 5 is housed, is substantially closed so that there is no likelihood of its mischievous removal, although when it is desired to substitute one card for another, the bolts 13 may be readily 20 removed, the old card withdrawn, and the new card inserted, and the parts then reassembled and clamped by the bolts.

It will be readily appreciated that the article possesses commercial value inasmuch as 25 one operating under the invention may solicit advertising, print the same upon the advertising card 5, and distribute the same gratis to hotels with the understanding that they will make use of the device and properly 30 display the same for a predetermined period of time as, for example, one year, a supply of call sheets sufficient for such period of time being given with the article.

It will be understood that any part of 35 the article may be made of any suitable material and that the article may be made in various sizes. It will also be understood that the call sheets may be secured in place in some manner other than that illustrated 40 in the drawings.

Having thus described the invention, what I claim is:

1. An advertising device comprising a 45 backing sheet, a sheet of transparent material marginally united to the said backing sheet and forming, with the backing sheet,

a pocket, an advertising medium fitted into the pocket with its display surface visible through the transparent sheet, the medium being so arranged that the advertising matter will be readable from one end of the device, and a call sheet secured upon the backing sheet and readable from the other end of the device. 50

2. An advertising device comprising a 55 backing sheet, a sheet of transparent material marginally united to the said backing sheet and forming, with the backing sheet, a pocket, an advertising medium fitted into the pocket with its display surface visible 60 through the transparent sheet, the medium being so arranged that the advertising matter will be readable from one end of the device, and a call sheet secured upon the backing sheet and readable from the other 65 end of the device, the upper marginal portion of the call sheet overlapping the mouth of the pocket whereby to substantially close said mouth.

3. An advertising device comprising a 70 backing sheet, a sheet of transparent material marginally united to the said backing sheet except at one edge and forming with the backing sheet, a pocket the mouth of which is located at the said free edge of 75 the said transparent sheet, an advertising medium fitted into the pocket with its display surface visible through the transparent sheet and readable from one end of the device, a plurality of call sheets disposed upon 80 the upper side of the backing sheet with their upper marginal portions overlapping the free edge portion of the said transparent sheet, and securing means fitted through the backing sheet, the said free marginal portion of the transparent sheet, and the said 85 call sheets and preventing removal of the said advertising medium.

In testimony whereof I affix my signature.

WELDON E. PENTICOFF. [I. S.]
